SHUTTLELESS LOOM AND WEFT-SELECTING MECHANISM THEREFOR

William Pool, Spondon, near Derby, England, assignor to Celanese Corporation of America, a corporation of Delaware

Application December 16, 1933, Serial No. 702,765
In Great Britain December 31, 1932

25 Claims. (Cl. 139—126)

This invention relates to shuttleless looms, that is looms in which the weft supply does not pass through the shed, and has particular reference to the presentation of weft to the inserting means in such looms, the principal object of the invention being to enable weft selection to be effected in looms of the type in which the weft is drawn into loop form prior to presentation to the inserting means.

10 There is described in U. S. application S. No. 484,785 filed 27th September, 1930 loop drawing means comprising movable trapping means adapted to bring weft trapped by said means into position to be engaged by loop drawing means, 15 said loop after drawing being carried into the warps. The invention relates to the type of weft measuring apparatus in which movable trapping means bring the weft into loop drawing position, and provides means for operating any of a plurality of movable trapping means so that selected 20 wefts can be drawn into loops and inserted into the warps in any desired order.

According to the invention, there is provided at the side of the loom a weft-measuring apparatus 25 comprising a plurality of movable trapping means supplied with weft from a corresponding number of packages, drawing means adapted to engage weft held at any one of said trapping means and draw it into a loop for insertion into the warps, 30 and selector means adapted to bring about engagement between the drawing means and any particular weft presented by the trapping means. The trapping means not only bring the selected 35 wefts into loop drawing position, but also maintain control over the weft during loop drawing and in the intervals when a loop is not being drawn in any particular weft.

Conveniently, weft not to be drawn into a loop 40 is held by the movable trapping means in a position where it will not be engaged by loop drawing means, the selector means operating to bring about the necessary movement of the trapping means for any weft as that weft is required. Moreover, means are preferably provided whereby 45 movement of non-selected trapping means is precluded during the operation of selected trapping means.

As indicated above, a loop is formed by the loop 50 drawing means in any selected weft presented by the movable trapping means. One loop drawing means may serve to draw loops in more than one weft, or a plurality of loop drawing means may be provided; in the particular embodiment described below there is a combination of these 55 arrangements, two loop drawing devices each

serving a pair of wefts. Conveniently, the loop drawing means proceeds continuously, as by being mounted on an endless chain, to pass the trapping means in one direction only. A succession of similar loop drawing devices may be arranged to pass the trapping devices successively, so that loops can be formed in close sequence.

Means are provided to release each loop when it has been drawn to the requisite length. If 10 each loop is sufficient to form a pick length, any weft can be inserted from one side of the loom either as single picks separated by one or more picks of other weft from that side, or as a succession of picks. Weft may be similarly inserted from the other side of the loom.

15 A pick of one weft is preferably connected to a further pick of the same weft, whether or not following the first pick in close succession. The two picks are thus laid in the fabric in the form of a loop, the bight of the loop binding the edge 20 of the fabric. For this purpose, each weft is severed from its package only after every other pick of that weft.

The trapping mechanism described in U. S. 25 application S. No. 484,785 filed 27th September, 1930 is particularly suitable for use with the invention, each weft being controlled by a plurality of trapping devices, one device moving to carry the weft to loop drawing position and another engaging the weft in readiness for a further movement to loop drawing position, and so on.

The movements of the trapping mechanism may be effected by means of a differential gear, one mechanism being driven by one side of the differential and the other by the other side. A 35 non-selected mechanism being held against movement, the other mechanism is freed and vice versa, without interrupting the drive to the differential gear. If a similar pair of trapping mechanisms is driven through a further differential gear and the two gears connected to the two sides of a third differential gear, locking of any three of the trapping mechanisms permits the fourth to be driven.

Suitable selector mechanism is operated from 45 a part of the loom driven in synchronism with the operating mechanism for the trapping and loop drawing means, e. g. a dobby or Jacquard, such selector mechanism also controlling directly or indirectly associated parts of the measuring apparatus in accordance with whichever weft is selected for loop drawing.

In the particular embodiment of the invention described below, each measuring apparatus 50 comprises four differential-driven rotatable members,

each carrying two trapping devices (one embodying a cutter), means for locking any three of the four rotatable members, an endless chain on which are mounted pairs of loop drawing carriers, and means under the control of the rotatable members to bring one of each pair of carriers into position to engage weft presented by the one rotating member. With a measuring apparatus at each side of the loom, as many as 10 eight wefts can be presented in many orders, the wefts varying in one or more of such characteristics as colour, lustre, dyeing properties, denier or counts, construction, and direction or degree of twist, and also material, e. g. natural 15 or artificial continuous filaments or staple fibres.

The accompanying drawings show by way of example a shuttleless loom adapted according to the invention to insert from each side of the loom any one of four wefts, the wefts being laid 20 as connected pairs of picks.

In the drawings:

Fig. 1 is a front elevation of the loom showing picking taking place of one of the weft threads supplied at the left-hand side of the loom;

Fig. 2 is a corresponding plan view of the loom; and

Fig. 3 is a side elevation of the loom viewed in the direction of the arrows 3—3 of Fig. 2, with the left-hand end of the shuttle race cut away.

Fig. 4 is a part sectional view showing the disc assembly and driving mechanism of the right-hand gear-box shown in Figs. 1 and 2. In this figure the upper right-hand disc is the one in operation, and in all subsequent figures of the gear-box the parts of the mechanism are shown in the positions conforming to this particular disc being in operation.

Fig. 5 is a part sectional plan view of the gear-box taken on the line 5—5 of Fig. 4, showing the main drive;

Fig. 6 is a diagrammatical part sectional view corresponding to Fig. 4 but showing part of the disc-selecting mechanism;

Fig. 7 is a plan view showing further parts of the selecting mechanism of Fig. 6;

Figs. 8 and 9 show controlling levers for the selecting mechanism.

Figs. 10—14 are detail views of the trapping and cutting devices carried by the discs shown in Figs. 4, 5 and 6;

Figs. 15 and 16 are plan views of the cam mechanism controlling the trapping and cutting devices taken on the lines 15, 16 respectively of Fig. 4;

Figs. 17, 18 and 19 show details of the weft-carrier mounting including springs for holding the carriers in any selected position;

Figs. 20 and 21 show in part sectional front elevation looking in the direction of the lines 20, 20 and 21, 21 respectively of Fig. 22 the mechanism for bringing one of the weft-carriers into operative position; and

Fig. 22 is an elevational view looking from the left-hand side of Fig. 20 with the two left-hand discs omitted; Fig. 22 also shows the chain sprocket by which the gear-box is driven.

Fig. 23 is a plan view of the controlling mechanism for the weft hook mechanism shown in Figs. 24—28, these figures showing the weft hook in various positions during its operation.

Figs. 29 and 30 are part-sectional side and front elevations respectively of a weft-length compensator mechanism;

Fig. 31 shows the controlling device for the compensator mechanism;

Fig. 32 shows diagrammatically a reversible drive provided for the lower discs shown in Fig. 4;

Fig. 33 is a detail of the drive to the gear box; and

Fig. 34 shows a preferred form of weft-inserting shuttle.

Figs. 35 and 36 show diagrammatically in side elevation and plan the carrier setting, releasing, and re-setting mechanism; in both of these figures the several different positions assumed by the weft carriers at different points along their run are clearly shown;

Figs. 37—44 show diagrammatically the sequence of operations followed in inserting two consecutive connected picks in one disc of a gear-box; and

Fig. 45 shows diagrammatically the operation of the weft hook shown in Figs. 23—28.

General arrangement

Figs. 1, 2 and 3 show the weft-measuring apparatus as comprising two units arranged one on each side of the loom, a weft length measured and inserted from one unit being followed by a length from the other unit as the shuttle is picked from side to side of the loom. Each unit comprises a rear chain-wheel 1 mounted on a shaft 2, the shaft 2 being driven by a chain gear 3 from one end of the crank shaft 4. A chain 5 passes from the chain-wheel 1 to a chain-wheel 6 of a gear box 7 mounted on the front rail 8 of the loom. A platform 9 mounted above each gear-box 7 carries the weft supply packages. The gear-box 7 is connected by radius rods 10 to a U-frame 11 mounted on the rear shaft 2, and bridging the chain-wheel 1. The shaft 2 is carried by bearings 12, the chain-wheels 1 being adjustable on the shaft from positions quite close to the bearings 12.

Gear-box and disc driving mechanism

As is seen by reference to Figs. 4 and 5 each gear-box 7 comprises upper and lower gear housings 21, 22 and shaft housings 23, 24 surrounding a tunnel-like space 25. In the lower and upper walls 26, 27 of the housings 21, 22 respectively are provided bearings 28a, 28b, 28c, 28d for spindles 29a, 29b, 29c, 29d to which are rigidly secured discs 30a, 30b, 30c, 30d within the tunnel 25, the pairs of discs 30a, 30b and 30c, 30d facing each other and the pairs 30a, 30c and 30b, 30d lying side by side.

In the subsequent description, similar parts associated with or operating in connection with each of the discs 30 are given the same reference numeral, and, where the description is applicable to each or all of the discs generally, such reference numeral is used alone. Where, however, the description relates to the operation of the member in connection with a particular disc, the reference numeral has added to it the suffix *a*, *b*, *c*, or *d* to correspond to the appropriate disc 30a, 30b, 30c, or 30d.

On the ends of the spindles 29a, 29b, 29c, 29d within the housings 21, 22 are secured gears 31a, 31b, 31c, 31d, the gears 31a and 31b being driven by gears 32a, 32b, and the gears 31c and 31d by gears 32c and 32d. The gears 32a, 32c are loosely mounted on vertical shafts 33, 34 respectively, while the gears 32b, 32d are secured to the lower ends of these shafts. At the upper ends of the shafts 33, 34 are arranged differential gears comprising pinions 35a, 35c secured to the gears 32a, 32c respectively and pinions 35b, 35d se-

cured to the shafts 33, 34 and therefore to the gears 32b, 32d respectively. The differential gears are completed by the bevel pinions 36, 37 respectively carried by housings 38, 39 rotatable 5 respectively about the shafts 33, 34.

The housing 38 is formed with a helical gear 40 and the housing 39 with a similar helical gear 41 as shown in Fig. 4. The gears 40, 41 mesh respectively with helical gears 42, 43 on horizontal spindles 44, 45 and are driven through pairs of gears 46, 47 from spindles 48, 49 terminating respectively in bevel pinions 50, 51 of a differential gear carried within a housing 52. A pair of bevel pinions 53 both meshing with the bevel pinions 50, 51 are freely mounted on a spindle 54 carried by the housing 52. The housing 52 is rotated by means of the chain-wheel 6.

The four discs 30a, 30b, 30c, 30d are thus connected by gearing to the chain-wheel 6, the one pair of discs 30a, 30b through the differential on the shaft 33 from the bevel pinion 50 on one side of the differential in the housing 52, and the other pair of discs 30c, 30d through the differential on the shaft 34 from the bevel pinion 51 on 15 the other side of the differential.

It is therefore possible for any one disc to be rotated positively from the chain-wheel 6 while all the remaining discs are stationary. Thus, assuming that the disc 30c is in rotation, as in fact 20 it would be with the mechanism in the particular positions shown in the drawings, the other discs 30a, 30b, 30d being locked stationary by means shortly to be described, the bevel pinions 35a, 35b of the differential on the shaft 33 will be locked 25 against rotation by reason of their connection to the locked discs 30a, 30b respectively, and in consequence thereof the housing 38 is prevented from rotation, this in turn locking the helical gears 40, 42 and, through the gears 46, the spindle 48 connected to the pinion 50 of the differential in the housing 52. The drive of the last-mentioned differential thus passes solely through the pinion 51 and through the spindle 49, gears 47 and helical gears 43, 41 of the differential on 30 the shaft 34. Again, the disc 30d being locked against rotation, the bevel pinion 35d connected to said disc through the shaft 34 is also locked so that the drive from the differential on the shaft 34 takes place solely through the bevel pinion 35c and the gears 32c and 31c to the disc 30c.

If the disc 30c is locked and one of the three other discs freed, that other disc will then be driven positively from the chain-wheel 6.

Disc locking and releasing mechanism

Connected with each of the disc-driving gears 31a, 31b, 31c, 31d is a projecting rim 56a, 56b, 56c, 56d respectively, each having two notches 57 (see particularly Figs. 6 and 7) on the opposite sides of its periphery. In connection with each disc 30a, 30b, 30c, 30d there is arranged a lever 58a, 58b, 58c, 58d respectively each provided with a projection 59 lying over a rim 56 and adapted to enter one of the notches 57 in the rim so as to prevent rotation of that particular disc. The levers 58a, 58c have a common pivot 60 and the levers 58b, 58d a pivot 61, and the outer ends of levers 58a, 58b and 58c, 58d are connected together by links 62, 63 respectively of such length 50 that if the projection 59 on the lever 58 of an upper disc 30 is in full engagement with its notch 57, the projection 59 of the disc 30 directly below is out of engagement with its respective notch 57.

The levers 58 and links 62, 63 thus afford a means for ensuring that either one of the upper

pair of discs 30a, 30c or one of the lower pair 30b, 30d is the one in rotation. This partial selection of the discs is effected as follows:

On the links 62, 63 are pins 64, 65 fitting into inclined slots 66, 67 in a slide 69 extending along the housing 21 and guided horizontally by rollers 70 running in slots 71 in brackets 72. A lever 73 provided with a fork 74 embracing a pin 75 on the slide 69 is secured to the end of a sleeve 77 surrounding a shaft 78 and freely rotatable thereon. The sleeve 77 is rotatable in a bearing 79 in the rear wall of the housing 21 so that both the shaft 78 and the surrounding sleeve 77 can be separately controlled from outside the housing by means to be described later.

A partial rotation of the sleeve 77 causes the slide 69 to be moved endwise, and, because of the inclination of the slots 66, 67 engaging the pins 64, 65, a lifting or lowering of the links 62, 63 simultaneously. The movement of the links 62, 63 is such that the upper projections 59 are completely engaged with their notches 57 while the lower projections 59 are completely freed, or vice versa.

The shaft 78 projects across the housing 21 and carries a lever 80 adapted to move lengthwise a slide 81, the slide 81 being provided with a slot 82 to accommodate the lever and allow it to pass below the slide for a purpose to be explained later.

Brackets 83 carry rollers 84 which engage slots 85 in the slide 81 and guide it towards the peripheries of circular plates 86, 87, secured below the helical gears 40, 41 by which the differentials on the shafts 33, 34 are driven. Each of the plates 86, 87 is provided with four equi-distant notches 88 adapted to receive the ends of the slide 81 so that a partial rotation of the shaft 78 controlling the slide prevents rotation of one or other of the plates, and thereby locks one or other of the differentials.

In this way, either the left-hand pair of discs 30a, 30b is locked against rotation while drive is transmitted to the differential of the other pair 30c, 30d, or vice versa. Moreover, since the sleeve 77 effects a selection between upper and lower pairs of discs, only one of the left- or right-hand pairs to which drive is permitted by operation of the slide 81 can rotate. Figs. 6 and 7 show the slide 69 pushed to the left to lift the links 62, 63, so restricting possible movement to discs 30a, 30c, and the slide 81 also pushed to the left, so further restricting movement to disc 30c.

Once rotation of the disc 30c has commenced, no other disc can rotate until the disc has completed a half-revolution. During that half-revolution, the projection 59c on the locking lever 58c rides on the rim 56c and thus prevents movement of the other three locking levers. At the same time, the end of the slide 81 adjacent to the plate 87 cannot move to the right until the next notch 88 is encountered. Since the gear 41 connected to the plate 87 drives the disc 30c through a differential of which the bevel 35d is locked, the gear 41 rotates at half the angular speed of the disc 30c, and the spacing of the notches 88 at 90° apart provides for a movement of the plate 87 between locking positions equal to a half-revolution of the disc 30c.

Although only one disc 30 can rotate at any one time, it is possible to effect a setting of the disc-selecting mechanism while a disc is rotating. For this purpose, levers 90, 91 secured to the sleeve 77 and shaft 78 respectively towards the rear of the loom (see Fig. 2) are operated by cords 92, 93.

through springs 93 which permit the cords to be pulled against the pull of return springs 94 even though the levers 90, 91 cannot be moved. Similarly the cords 92 can be slackened. When the disc has completed its movement, the projection 58 on the locking lever 58 can drop into the next notch 57 in the rim 56 and the one end or the other of the slide 81 can drop into the next notch 88.

10 Either or both of the levers 90, 91 can then move under the control of the springs 93, 94 to select another one of the discs 30 for rotation. If no change is made in the setting of the levers 90, 91, the same disc continues in operation.

15 The possibility of setting the disc-selector mechanism while one disc is in rotation enables selection to be performed unhurriedly, and also allows of selection being carried out by mechanism which need not be accurately in phase with the disc operation, as will appear later.

20 As will be seen from Figs. 6 and 7, the notches 57 of the rims 56 connected to the lower discs 30b, 30d have one edge inclined, the corresponding projections 59 being similarly shaped. The 25 notches 57 and projections 59 of the upper discs 30a, 30c are square sided. Thus if by any mischance, such as the breaking of one of the control cords 92, the levers 58 arrive at an intermediate position, the inclines on the lower pairs 30 of notches and projections 57, 59 will force the lower levers 58 out of engagement as that disc rotates and bring the upper levers 58 into engagement.

25 Similarly, the notches on the left-hand plate 35 86 have one side inclined, the left-hand end of the slide 81 being correspondingly shaped. Hence, rotation of the plate 86 against the slide 81 will force the slide firmly into engagement with the other plate 87 if the slide has been incompletely moved.

30 The above provisions prevent serious damage occurring to the mechanism if the selection gear fails to operate properly.

35 Though the drive may suddenly be transferred 40 from one of the side differentials to the other, the robust, directly-controlled slide 81 easily brings the one differential to rest, there being relatively little force needed to drive the mechanism. This leaves the levers 58 to effect only the transfer of 45 drive between the top and bottom bevels 35 of the side differentials. The levers 58 are made stout enough to make this transfer without danger of bending and buckling.

Disc construction

50 The discs 30a, 30b, 30c, 30d are arranged in pairs symmetrically about the centre line of the gear-box 7 and also symmetrically above and below the lower run of the chain 5 as it passes from the chain-wheel 6 to the chain-wheel 1, this lower run following a substantially horizontal path through the tunnel 25. Each disc 30 is bored at diametrically opposite points to receive sleeves 100 forming bearings for spindles 101 (see 55 Figs. 10 and 14).

55 At the sides of the discs 30 facing towards the chain 5, each spindle 101 is provided with a fibre pad 102 and a rubber washer 103 held in place by a slotted clip 104 (Fig. 11) slipping into slots 105 60 near the end of the spindle 101, and at its other end with a projection 106 adapted to be engaged by a cam during rotation of the disc 30 so as to push the fibre pad 102 away from the projecting end of the sleeve 100, thus leaving a gap into which 65 weft thread can enter. A spring 107 secured to

the disc 30 and having its ends acting in slots 108 under the projections 106 on the spindles 101 normally urges each fibre pad 102 into contact with the end of its sleeve 100, the tendency being for the pad to trap any thread lying between it and the end of the sleeve 101.

65 The cams operating the spindles 101 of the several discs are carried by circular plates 109, 110 clamped against the walls of the housings 21, 22 facing the discs 30, the plates carrying 10 curved cam projections 112, 113 which have a certain amount of angular overlap (see Figs. 15 and 16), the operative portion of the cam thus extending from the free end of the one piece 112 to the free end of the other piece 113.

70 The projections 106 on the spindles 101 of the trapping devices of each disc are carried by the rotation of that disc into contact with the projections 112, 113, riding up a ramp 114 on the free end of the projection 112 and dropping sharply on reaching the square end of the continuing projection 113.

75 The combined length of the projections 112, 113 may be adjusted by means of worm gears 115 engaging teeth 1150 extending round part of the circumference of the plates 109, 110 so that both the commencement and the finish of the cam operation may be accurately adjusted to any required point in the rotation of the disc. The worms 115 are carried by bearings 116 formed by turning over projections of plates 117 lying between the cam plates 109, 110 and the wall of the corresponding housing 21, 22. The plates 117 are secured in position by nuts 111 about which the cam plates 109, 110 can be rotated by the worms 115.

80 Fig. 15 shows cams 112a, 113a and 112c, 113c for operating the spindles 101 carried by the discs 30a, 30c, the cams for discs 30b, 30d being shown in Fig. 16. The arrows show the cam-settings for 40 discs 30a, 30b and 30d to be arranged for anti-clockwise rotation of the discs, whereas the cams for disc 30c are arranged for clockwise rotation of the disc. The reason for the reverse rotation of the disc 30c will appear below.

85 One of the spindles 101 of each disc 30 is provided with a notch 119 whose one edge 120 (see Fig. 10) is adapted to pass the end of the sleeve 100 as the cam permits the spring 107 to retract the spindle 101. A weft thread which has entered 50 the gap between the sleeve 100 and the fibre pad 102 and lies close to the spindle 101 is thus severed by the cutting action between the edge 120 of the notch 119 and the inner edge of the sleeve 100. One end of the thread adjacent the point 55 of severing remains held between the pad 102 and the end of the sleeve 100, while the other end is freed from the pad, the pad having a notch 121 on one side to clear the thread. There being no notch 119 on the other spindle 101 of the 60 disc, no cutting takes place at that spindle. The pad 102 is held in correct position on the spindle 101 by the squared end of the spindle 101 engaging a corresponding shaped hole in the pad.

65 The functions of the trapping and severing devices on the spindles 101 are clearly seen in Figs. 10 to 14. In these figures (as also in some subsequent figures), trapping devices provided with cutting devices are designated as "A" and non-cutting trapping devices as "B". At the left-hand 70 side of Fig. 10 a non-cutting trapping device B is shown with its spindle-head 106 depressed by the cams 112, 113 to bring the pad clear of the end of the sleeve 100. When the disc 30 is rotated to bring the head 106 of the spindle 101 clear of 75

the run formed by the overlapping cams 112, 113, the spring 107 snaps the head upwardly so that the pad 102 closes quickly on to thread lying between itself and the sleeve 100.

- 5 Whenever the non-cutting trapping device B of any disc comes to rest opposite a short-lift cam 122 secured to the cam plate 109 (as happens after every full revolution of the disc), the cam 122 engages an inward extension 123 of the head 106 and depresses the head slightly, as shown in Fig. 12, to relieve the full pressure of the pad 102. The rubber washer 103 ensures, however, that the pad 102 continues to press lightly on thread which (as explained hereafter) lies between the 10 pad and the sleeve 100 when the spindle 101 occupies this position. The cutting trapping device A has no such extension 123 and so avoids the 15 relieving action of the cam 122 as it passes the cam.
- 20 The head 106 of the non-cutting trapping device B also has forward and rearward extensions 124 and 1124 which vary the timing of the device B as compared with the timing of the device A. The purpose of these timing provisions will be 25 explained later.

At the right-hand side of Fig. 10, the head 106 of the device A is shown clear of the cams 112, 113. The thread having been cut by the edge 120, one end of the thread lies over the notch 121 (see 30 Fig. 14) and is released while the other is held by the pad 102.

The sleeve 100 is of hardened metal and its lower face is ground to form a sharp cutting edge round its bore for co-operation with the edge 120 35 on the spindle 101. A spring 125 keeps the side of the spindle 101 bearing the edge 120 firmly against the side of the sleeve 100 to ensure clear cutting of the thread. The sleeves 100 are held in place by screws 126.

40 Weft-drawing carriers

The chain 5 has at two points in its length a link pin 130 (see Fig. 17) which is extended to provide a bearing at each end for a short sleeve 45 131 to which is secured a carrier bracket 132. Each bracket bears a pair of pegs 133 at distances from the centre line of the chain which brings the pegs to symmetrical positions with respect to the centre line of the discs 30 on that side of the 50 chain (see Figs. 4 and 21).

The sleeve 131 being freely mounted on the extended pivot pin 130, the bracket 132 can be swung towards either of the discs 30 on its side of the chain 5, and also to an intermediate position. In Fig. 4, the right-hand carrier bracket 55 132 has been swung upwardly to bring the pegs 133 between the trapping devices of the disc 30c in operation. The carrier bracket 132 on the left-hand side lies at 90° to the right-hand bracket 60 so that the pegs 133 trail behind the link pin 130 and pass clear of both the discs 30a and 30b.

Carrier control

In order to bring the carrier pegs 133 into any 65 of the three possible positions which they may assume, i. e. upwardly or downwardly to face a disc or intermediately to trail between the discs, each bracket carries a pair of short pins 134 and a long pin 135 arranged equidistantly from the link pin 130, and projecting towards the chain. As the chain 5 follows its run, and before the carriers reach the discs 30 control members operated 70 in accordance with the particular disc in rotation engage the pins 134, 135 to set one carrier in oper-

ative position and the other in a trailing or idle position.

The horizontal run of the chain 5 from the chain-wheel 6 through the tunnel 25 is controlled by means of upper and lower guides 140, 141 which are generally of U-section so as to be rigid in character (see Fig. 17). Formed on the outer face of the base of the U are two grooves 142 to pass the links of the chain freely while forming projections 143 bearing against the rollers 144 10 of the chain, as well as against rollers 1144 on the spindle 130. The chain 5 and carriers 133 are thus held against vibration; at the same time, since the contact of the guides 140, 141 is only against the rollers, the chain can be drawn very 15 easily along the guides.

Where the guides 140, 141 pass through the tunnel 25, their flanges are cut away, as shown clearly in Fig. 22, leaving only the portions of 20 the guides carrying the grooves 142 to pass between the discs 30. These portions are rigidly held by brackets 1140, 1141 carried by the gearbox 7.

Immediately in advance of the discs 30, i. e., 25 just as the chain 5 is entering on its horizontal run after leaving the chain-wheel 6, the carriers pass projecting teeth 145 on the forked ends of levers 146, 147, there being two teeth 145 on each lever, all pointing towards the chain 5. Two opposing teeth lie on one side of the chain and two 30 on the other. This is clearly shown in Fig. 35, which also shows how the levers 146, 147 lie between the flanges of the guides 140, 141 to rock on pivots 148 on the guides. The forked ends of 35 the levers 146, 147 carrying the teeth 145 are connected together by strips 149 and links 150 passing round the carrier pegs 133 (see Fig. 20) so that the levers 146, 147 must move simultaneously either downwards to bring the upper pairs 40 of teeth 145 at their forked ends into the paths of the pins 134 on the carrier brackets 132, or upwards to bring the lower teeth 145 into the paths of the pins 134.

The levers 146, 147 are controlled in the following manner in accordance with the disc in 45 rotation being on an upper or lower pair. Referring to Figs. 20 and 22, it will be seen that the underside of the slide 69 is provided in a substantially central position with a notch 151 having an inclined side 152 lying above the head of a 50 plunger 153 passing through the lower wall of the housing 21 and pivoted at its lower end to the upper lever 146.

With the slide 69 pushed to the left to enable 55 one of the upper discs 30a, 30c to rotate, the head of the plunger 153 lies freely in the notch 151 and the lever 146 is held in a raised position by a spring 154. By its connection with the lever 146, the lower lever 147 is also held raised and the teeth 145a, 145c on the lever 147 come into 60 the paths of the short pins 134 on the carrier brackets 132.

When the slide 69 is pushed to the right to enable one of the lower discs 30b, 30d to rotate, 65 the inclined edge 152 of the notch 151 forces the plunger 153 downwardly against the pull of the spring 154 and the teeth 145b, 145d on the upper lever 146 come into the paths of the short pins 134 on the carrier brackets.

The carrier brackets 132 on the two sides of 70 the chain 5 approach the teeth 145 with the pegs 133 in a trailing position (see Figs. 20 and 22) so that there is one short pin 134 of each bracket above the link pin 130 and another below the link pin. Therefore, an upward movement of 75

the teeth 145 caused by either of the upper discs 30a, 30c being in rotation brings the lower teeth 145a, 145c into the path of the lower pins 134a, 134c on the brackets 132 at each side of 5 the chain and throws the brackets counterclockwise about the link pin 130, i. e. the carrier pegs 133 are thrown upwardly towards the discs 30a, 30c.

If, on the other hand, either of the discs 30b, 10 30d is in rotation, the upper teeth 145b, 145d engage the upper pins 134b, 134d to throw the carrier brackets clockwise and the carrier pegs downwardly towards the discs 30b, 30d. In this 15 way, a preliminary setting of carrier pegs towards the upper or lower pairs of discs 30 of which one is in rotation is effected.

The carriers are shown facing both discs 30a and 30c in Fig. 21.

Further controlling means are provided to 20 turn one set of carrier pegs to idle position away from the non-rotating disc of the pair, leaving only the one set of pegs in operative position with respect to the one disc in rotation. This further control is effected by means of the lever 25 80 controlling the slide 81 to effect selection between left- and right-hand pairs of discs.

After passing through the slot 82 in the slide 81, the lever 80 is forked at 155 to embrace a lever 156 mounted on a pivot spindle 157 passing 30 through the lower wall of the housing 21.

A lever arm 158 extends forwardly from the lower end of the spindle 157 and passes through a clearance slot in the bracket 1140 to enter a hole 159 in a lever 160 pivoted on an extension 35 of the bracket 1140. A similar lever 161 is pivoted on the lower bracket 1141.

The levers 160, 161 are connected together by a stirrup 162 surrounding the run of the right-hand carrier bracket 132 and pivoted at 163 to 40 a freely hanging lever 164 carried by the wall of the shaft housing 24. By this connection, the lever 161 moves simultaneously with the lever 160.

The ends of the levers 160, 161 engage prongs 45 165 on slides 166, 167 carried by the chain guides 140, 141 and terminating at their ends in teeth 168a, 168b, 168c, 168d pointing towards the chain 5. Movement of the slide to the left to permit one or other of the plates 86, 87 to rotate under 50 the control of the shaft 78 produces through the connections just described a corresponding movement to the left of the slides 166, 167, thus bringing the tooth 168a into the path of the long pin 135 carried by the left-hand carrier bracket 132, which pin 135 has previously been brought 55 to a position above the link pin 130, as in Fig. 21. The engagement of the pin 135 with the tooth 168a returns the pegs 133 on the left-hand bracket 132 into a trailing, that is non-operative, position. The movement of the tooth 168c to 60 the left simultaneously with the tooth 168a brings the tooth clear of the long pin 135 of the right-hand carrier bracket 132, thus allowing the pegs 133 of that bracket to remain in operative position with respect to the rotating disc 30c.

A similar pre-setting of both sets of carrier pegs 133 towards one pair of discs 30 comprising the one in operation followed by a returning of one set of pegs 133 away from the disc not 70 in operation is effected if any one of the other discs 30a, 30b, or 30d is in operation, the setting of the teeth 145, 168 being automatically controlled by the disc-controlling mechanism.

In order to retain the carrier brackets 132 in 75 the positions to which they have been set, either

operative or non-operative, each sleeve 131 to which the brackets are secured is provided with a square 169 embraced by the two blades of a U-spring 170 having its free ends clamped to an out-turned extension 171 of a chain link 172. 5 Thus, the sleeves 131 are free to turn by expanding the springs 170 when the carrier 132 is rotated by engagement of the teeth 145, 168 with the pins 134, 135, this overcoming the pressure of the springs on the faces of the squares 10 169. When the carriers have been set, the springs 170 are strong enough to hold an operative carrier in position against the pull of a weft thread engaged by the pegs 133 of that carrier, as well as to hold an inoperative carrier against accidental displacement. 15

It will later be described how weft thread is led to each of the discs 30, but for the moment it will suffice to say that as a selected disc is freed for rotation, weft thread held by one trapping device of that disc is engaged by the other trapping device, and the length of thread extending between the two trapping devices is engaged by the pegs 133 of the carrier which has been selected and brought into a position where they will be carried by the chain to pass between the two trapping devices. One end of the thread being held by one trapping device, the movement of the carrier pegs 133 thus results in the formation of a loop, the thread being drawn from 30 the supply package past the other trapping device. In this respect, the loop-drawing operation is similar to that described in U. S. application S. No. 484,785 filed 27th September, 1930. 35

Weft-hook mechanism

As will be explained more fully later, consecutive picks of weft drawn from any disc 30 are connected together, so that after the first pick of each pair has been inserted it extends from the 40 edge of the fabric to one of the trapping devices of the disc. With three of the four discs, this length of weft lies clear of the loop-drawing mechanism; with the upper disc on the side of the chain 5 remote from the fabric, i. e., in the 45 right-hand gear-box, the disc 30c, it is necessary to draw the length of weft connected to an inserted pick and running back to the non-cutting trapping device on the disc 30c into a position where it will not be engaged by the carrier pegs 50 133. For this purpose a rod 190 terminating in a hook 191 is provided to engage this length of weft and to draw it out of the path of the carrier. In the mechanism illustrated, the length is drawn to a position below the carrier run. The 55 hook 191 is controlled from the disc 30c in the following manner:

Carried within the housing 21 by the gear 31c connected to the disc 30c is a plate 192 carrying on its upper surface two diametrically opposed 60 rollers 193, and lying across the plate 192 in a position to be engaged by the rollers 193 when they are rotated with the plate is a lever 194 pivoted at 195x and having its free end connected by a link 196 to a lever 197 on a spindle 198x 65 extending through the rear wall of the housing 21. Outside the housing, the spindle 198x carries a lever 199 to which is pivotally connected at its lower end a lever 200 carrying the hooked rod 190. 70

A stop 201 formed by bending over the end of the lever 199 limits the movement of the lever 200 in a clockwise direction. A spring 202 connected to the lever 199 above the spindle 198x urges the lever 199 in a counter-clockwise direc- 75

tion. The lever 200 carries a pin 203 adapted to co-operate with the edge of a cam plate 204 secured to the rear wall of the gear box. When the lever 194 is free from both of the rollers 193, the spring 202 pulls the lever 199 counter-clockwise until the pin 203 reaches the right-hand end of the plate 204, as shown in Fig. 24.

As the plate 192 rotates with the disc 30c, one of the rollers 193 is carried against the edge of the lever 194 (see Fig. 23), so moving the lever to the right and causing the lever 199 to move in a clockwise direction against the pull of the spring 202 to move the lever 200 and with it the hook 191 underneath the disc 30c. The lever 200 outweighs the rod 190 and keeps the pin 203 clear of the lower face of the cam plate 204.

In Fig. 25, corresponding to the showing of disc 30c in Fig. 4, the disc is half-way through its half-revolution of movement, and the hook 191 is moving towards the position at which it meets the thread. Fig. 26 shows the lever 199 substantially at the limit of its clockwise movement, with the hook 191 lifted to engage the length of weft thread held by the non-cutting trapping device B shown at the left-hand side of the disc 30c. The disc is rotating clockwise (see the arrow in Fig. 23), and the trapping device B is therefore receding from the plane of Fig. 26 and moving to the right.

The disc 30c completes each half-revolution of movement with the trapping devices occupying a central position shown dotted in Fig. 26, the further rotation of the plate 192 with the disc permitting the lever 194 to return to its original position and allowing the spring 202 to move the lever 199 in a counter-clockwise direction until the lever 200 and the hook 191 have reached the position shown in dotted lines, corresponding to the idle position of the hook 191 shown in Fig. 24. This time, however, the hook 191 holds the weft length, and retains the length in the position shown dotted in Fig. 26.

This thread is thus drawn into a position where it will not be engaged by the carrier pegs 133, and is held in that position until the disc 30c makes a further half-revolution, whether or not such further half-revolution follows immediately after the one through which the weft is engaged or after an interval occupied by the insertion of weft drawn at other discs.

The second of the rollers 193 on the plate 192 comes into contact in such further half-revolution with the lever 194 and again causes the lever 199 to move in a clockwise direction. This time, however, the pull of the thread on the hook 191 overcomes the over-balancing effect of the lever 200 and brings the pin 203 into contact with the lower edge of the cam plate 204, as shown in dotted lines in Fig. 27. Instead, therefore, of the pin remaining clear of this edge, it is carried into and along a slot 205 cut in the plate 204 to cause the lever 200 to rise with respect to the lever 199 and the hook 191 to be depressed, bringing the hook towards the direct line from the edge of the fabric to the trapping device, which by this time has moved towards the right somewhat and is also moving away from the hook (see full-line position of the hook in Fig. 27).

The left-hand end of the slot 205 slopes sharply upwards as shown at 206 to bring about a sudden depression of the hook 191, so permitting the engaged weft to be released. This sudden release is assisted by a small projection 207 (see Fig. 23) on the face of the lever 194 engaged

by the rollers 193, so that the lever 194, and with it the lever 199 is given a rapid movement at the instant when the hook 191 is moving sharply downwards because of the pin 203 passing up the inclined portion 206 of the slot 205. Fig. 28 shows the final position of the advanced hook 191 and the released weft proceeding directly from the trapping device towards the edge of the fabric.

It will be understood from the foregoing description that the weft hook 191 only engages weft from the disc 30c. When any of the other discs is in operation no such drawing of the weft to one side is necessary. If, therefore, only three wefts have to be inserted from one gear box, the disc 30c can be held permanently out of action and the weft hook and associated mechanism dispensed with.

Driving arrangement of disc operating with weft hook

It is necessary, by reason of the weft from the disc 30c having to be drawn aside by the hook 191 between consecutive picks, to change the direction of rotation of the disc 30c so that instead of all discs rotating in the same direction, the upper pair of discs rotate in opposite directions. This is effected in the first place by the pairs of gears 40, 42 and 41, 43 (see Fig. 5 being of opposite hand, so that the shafts 33, 30 34 rotate in opposite directions. Secondly, in the drive to one of the lower discs (in the right-hand gear-box, the disc 30d) is inserted an idle gear. For this purpose a stub axle 180 is arranged within the housing 22, as shown in Fig. 4, 35 to carry a pair of connected pinions 181, 182, the pinion 181 meshing (as in Fig. 32 (b)) with the gear 31d connected to the disc 30d, and the pinion 182 meshing (as in Fig. 32 (a)) with the gear 32d at the lower end of the shaft 34, so 40 that instead of the gears 31d, 32d meshing directly and rotating in opposite directions, they mesh indirectly through the pinions 181, 182 and so rotate in the same direction. Therefore, notwithstanding the reverse rotation of shaft 34, 45 the disc 30d driven by the shaft rotates in the same direction as the discs 30a, 30b driven by shaft 33.

When the gear-box is used on the other side of the loom, the discs 30b, 30d must rotate in the same direction as disc 30c, leaving upper and outer disc 30a rotating in the opposite direction to work in conjunction with a weft hook 191. In order to reverse discs 30b, 30d, the pinions 181, 182 are removable, and the gear 32d can be inverted on the shaft 34 so as to mesh directly with the gear 31d instead of through the pinions 181, 182, (see Fig. 32 (c)). Provision is made at 183 for a similar stub axle 180 to be mounted adjacent the gears 31b, 32b driving the other lower disc 30b, so that by similar interposition of the pair of pinions 181, 182 and inversion of the gear 32b, the direction of rotation of the disc 30b as well as of disc 30d may be reversed for operation of the gear-box at the other side of the loom.

Compensator control mechanism

As has previously been described, only one trapping device A on each disc is provided with weft cutting means, the cutting only taking place after the insertion of two picks from that disc so that the first pick inserted from a particular disc remains connected to the supply and is held for the time being by the non-cutting trapping device B of that disc. It follows, therefore, that between

the inserted pick and the disc there remains an excess length of weft which has to be provided for in the drawing of the loop which forms the first pick. In other words, the first pick loop must contain a greater length of weft thread than the second pick loop.

Means are therefore provided to enable compensation to be effected between the lengths of consecutive loops drawn at any one disc, whether or not such loops are drawn in immediate succession or with an interval between. Such compensating means are shown in Figs. 29 and 30 and are controlled by means of a rod 210 running parallel to the chain 5 and passing through the rear wall of the gear-box (see Fig. 31). The rod 210 terminates in a head 211 between which and the wall of the gear-box is arranged a compression spring 212 urging the head 211 against the end 213 of a lever 214 pivoted at 215x within the shaft housing 24. A similar lever 216 pivoted at 217x in the shaft housing 23 at the other side of the gear box is connected to the lever 214 by a link 218.

Below the gear 32a and secured thereto is a cam 219a, and immediately below the cam and secured to the shaft 33 is a similar cam 219b. Similar cams 219c and 219d are secured to the gear 32c and the shaft 34 respectively.

The lever 216 is engaged at its end 220 by either of the cams 219a, 219b when these cams rotate, i. e., when either of the discs 30a, 30b rotates, and the lever 214 is similarly engaged at its end 213 adjacent to the head 211 on the rod 210 by one of the cams 219c, 219d when either of the discs 30c, 30d rotates. The cams 219 are so positioned relative to the axes of the shafts 33, 34 that in the half-revolution of any of the discs 30 in which a first pick is to be drawn, the corresponding cam 219 (though rotating with the disc) moves into contact with its lever 214 or 216 and by overcoming the spring 212 moves the compensating device through the rod 210 into a position in which it causes extra weft to be taken into the loop being drawn, the compensating device operating in conjunction with all the discs 30, as described below.

In the half-revolution of any of the discs 30 in which a second pick is drawn, the corresponding cam rotates clear of its lever 214 or 216, and the spring 212 acting through the rod 210 renders the compensating device inoperative.

It may here be pointed out that the above description with reference to Figs. 4-28 and 31 and 32 completes the explanation of the construction and function of the gear-box 7 and the parts mounted in or on the gear-box (with the exception of a mere detail of drive adjustment shown in Fig. 33 and an explanation of the different adjustments between right- and left-hand gear-boxes), and it will therefore be clear that the gear-box is a complete unit entirely self-contained as regards the various mechanisms operating the discs to bring any selected weft into position to be drawn into a loop.]

65

Compensator mechanism

Adjustably mounted on the radius rods 10 is a bracket 227 surrounding the path of the carriers as they pass towards the rear of the loom. On one side of the bracket 227 is pivoted a lever 228 connected at its upper end to the link 210. Forming the pivot of the lever 228 in the bracket 227 is a spindle 229 lying below the chain run, a similar spindle 230 pivoted in the bracket 227 above the chain run being connected by a lever 231 to the

lever 228, a slight amount of play being afforded in the pivot connection 232.

The spindles 229, 230 each carry a pair of forwardly extending rods 233, the pair of rods 233a, 233b lying on the side of the chain corresponding to the discs 30a, 30b, and the pair of rods 233c, 233d lying on the side of the chain corresponding to the discs 30c, 30d. Each of the rods 233 is forked at its forward extremity to receive an unglazed porcelain thread guide 234.

Whenever one of the discs 30 is being used to draw the first of a pair of connected picks, the link 210 is pushed by one of the cams 219 against the action of the spring 212 to move all the four rods 233 simultaneously, the upper rods downwardly and the lower upwardly, thus bringing all the guides 234 towards the paths followed by the pairs of carrier pegs 133. The rods 233 are so positioned moreover that one of the guides 234 lies between a pair of carrier pegs 133 (see Fig. 25) whatever the pair of pegs in operation, so that as the length of weft lying between the pegs 133 in loop-drawing operation is engaged by the guide 234 the continued motion of the pegs 133 results in an additional compensating loop being drawn by 25 the guide 234 within the main loop. Such a compensated loop is shown drawn from a left-hand disc of the left-hand gear-box in Fig. 2.

When, however, the loop under formation is a second pick loop, the corresponding guide 234 is held by the link 210 under the pull of the spring 212 (all of the cams 219 being inoperative) clear of the loop drawing carrier pegs 133 so that a simple main loop is drawn. The length of each compensating loop for the first picks can be 35 adjusted by varying the extent to which the rods 233 project forwardly from their supporting levers 231, 232.

The link 210 is made in two parts for ease of assembly, the part terminating in the head 211 within the gear-box 7 being connected to the external part by the coupling 1210.

Loop release mechanism

Release of each weft loop is effected as soon as the carrier pegs 133 have travelled sufficiently towards the rear of the loom to have drawn the loop to the requisite length by bringing about a rearward rotation of the carrier bracket 132. For this purpose toothed members 235 are provided on the rear ends of the levers 146, 147 which carry at their forward ends the carrier setting teeth 145. As shown in Fig. 35, the members 235 extend respectively downwardly from the upper lever 146 and upwardly from the lower lever 147 and are each provided with pairs of teeth 236a, 236b, 236c, 236d adapted to engage the pins 134, 135 on the carrier brackets 132.

A downward movement of the levers 146, 147 brings the pairs of teeth 236a or 236c on the lever 146 into engagement with the one pin 134 and the pin 135 on a carrier bracket which has drawn a loop from either of the discs 30a or 30c, so as to rotate the carrier bracket rearwardly 60 through 180°, during which rotation the weft falls away from the pegs 133. Similarly an upward movement of the levers 146, 147 brings the teeth 236b or 236d on the lever 147 into contact with pins 134, 135 on the carrier drawing a loop from 70 one of the lower discs 30b, 30d to release that loop.

Since the ends of the levers 146, 147 are raised at the gear-box 7 to throw the carriers towards the upper pair of discs 30a, 30c (as described with 75

reference to Figs. 20 and 22), the simultaneous downward movement of the other ends of the levers 146, 147 automatically brings the teeth 236a or 236c into position to engage pins 134, 135 on the one carrier bracket 132 which the teeth 168 (see Fig. 21) have allowed to remain in its upward position.

It is preferred to provide two weft releasing teeth 235 on each member 235 because then the 10 carrier brackets are given a full half-revolution of releasing movement, and clean release of the weft loop is thereby ensured.

The members 235 are adjustably positioned on the levers 146, 147 so that weft release can be 15 adjusted to any point along the rearward run of the carriers, in accordance with the loop length required. Since, however, the upward and downward movement of the members 235 will vary in extent in accordance with their distance from 20 the pivots 148 of the levers 146, 147 on which the members 235 lie (it being noted that the upward or downward movement of the forward ends of the levers 146, 147 is fixed by the movement of the lever 155), the pivots 148 of the levers 146, 25 147 are adjustable along the chain guides 140, 141 so that whatever the positions of the members 235 they have substantially the same up and down movement. Accordingly, a plurality of pivot holes 237 is provided along each of the guides 140, 141 30 (see Figs. 3 and 29).

Since each loop must be released at the instant the inserting member is ready to receive it to carry it into the warps, the timing of the loop drawing operation is determined from the 35 time of arrival of the carrier pegs 133 at the releasing teeth 236, which teeth are positioned in accordance with the loop length required. The drive of the chain 5 is therefore adjusted so that the carrier brackets 132 on the chain arrive at 40 the teeth 236 at the same time in each pick-inserting cycle, and so reach the discs 30 earlier in the cycle when a longer loop is to be drawn and later in the case of a short loop. The gearbox 7 being driven by the chain 5, the setting of 45 the chain run to effect loop-release at the correct moment automatically advances or retards the disc operation in accordance with the different time in the cycle at which the carriers 133 may arrive at the discs when the apparatus is 50 set to weave different widths of fabric. As the selection of the discs 30 can take place while any disc is in rotation (as described with reference to Figs. 6-9) any variation in the point in the cycle at which the discs must commence 55 their rotation need not interfere with the setting of the control mechanism for selecting the discs.

The uniform time of release for all the loops necessitates the teeth 236 being arranged at substantially the same distances from the discs 30, 60 and calls for the equi-distant spacing of the carrier brackets 132 along the chain 5. In practice, two carrier brackets 132 form a convenient number to enable the loops to be drawn in close succession.

65 Carrier re-setting mechanism

Since after release of the weft loops the carriers are given a rotation to 180°, they continue 70 their travel projecting to either the upper or the lower side of the chain 5. In order to return them to the trailing position in which they are ready to be set by the teeth 145, the pins on the carriers encounter fixed teeth 238 mounted on the chain guides 140, 141 towards their rear end. 75 One of these teeth engages the pin 135 on the

carrier which has been in operation and rotates the carrier rearwardly through 90°, i. e., into trailing position.

Loop formation

5

Before describing the operation of the weft measuring apparatus as a whole and the manner in which weft selection is obtained, the method of loop formation at any particular disc will be described with reference to the diagrammatic Figs. 37-44. The operations shown in these figures correspond to discs 30a, 30b, and 30d of the gear-box 7 at the right-hand side of the loom. With the reversed disc 30c there is a slight variation in operation, this being shown by Fig. 15 45. Figs. 37-44 should be read particularly in conjunction with Figs. 10-16.

The position of rest of any disc is with the two trapping devices lying along the line of travel of the carrier serving that disc. If the first of a 20 pair of connected picks is to be inserted from the disc, the trapper A incorporating a cutter (shown as a solid circle in Figs. 37-45) holds the end of a weft thread, while the trapper B having no cutter (shown as open circle) lies just clear 25 of the length of weft 250 extending from the guide 251 by which the thread is directed to the disc and to the trapper A (see Fig. 37).

All the discs 30a, 30b, 30d move with a counter-clockwise rotation, i. e., the trapper A moves to 30 the left (i. e., towards the edge of the fabric 252) and the trapper B to the right so that the trapper B engages the weft thread (see Fig. 38). At this time, the head 106 of the spindle 101 of the trapper B is held depressed by the cam 112, and the 35 weft 250 therefore passes between the pad 102 and the sleeve 100. A length of thread is thus carried between the trapping devices A, B transversely to the path of the carrier pegs 133 which, as soon as the trappers A, B have rotated sufficiently, pass 40 between the trappers and commence to draw the length of weft into a loop 254, as shown in Fig. 39. During the loop drawing operation the trapper B remains open, so that the weft is drawn freely 45 from the supply through the guide 251.

The loop being intended for a first pick, the compensator peg 234 has been brought into position to engage the weft between the pegs 133 so that an additional loop 255 is drawn within the 50 main loop 254 to provide for the length of weft 256 extending between the edge 253 of the fabric and the disc 30 after insertion of the pick (see Figs. 40 and 42). The carrier pegs 133 continue to draw the loop until the pins 134, 135 on the carrier bracket 132 encounter the teeth 236, the 55 pegs 133 then being thrown rearwardly to release the loop as shown in Fig. 41.

The end of the loop 254 is released by the trapper A encountering the cam 112, the other trapper B leaving the continuation cam 113 to seize 60 the other part of the loop leading back to the guide 251, and the loop is presented (by means to be described hereafter) to the dummy shuttle 257, the shuttle at this instant being picked across to the left-hand side of the fabric to carry the 65 thread in the loop into the warps (see Fig. 41). The lag extension 1124 on the head 106 of the trapper B delays the trapping action of the trapper until the weft has been released from the pegs 133. This avoids straining of the weft.

The cam 112 is so adjusted that the trapper A retains its hold on the end of the loop 254 until the shuttle has passed part-way into the shed, thus preventing the shorter part of the loop between the shuttle and the trapper A from be- 75

ing drawn out of the shuttle until the shuttle has crossed the whole width of the warps.

The shuttle releases the weft end as it leaves the other side of the warps and the weft thread is drawn taut and beaten up, leaving the length 258 extending between the inserted pick 258 and the trapper B. The trappers come on completion of their half-revolution into the positions shown in Fig. 42, the trapper B retaining its hold on the weft until a further loop has to be drawn from the same disc 30 to complete the second of the pair of connected picks.

Such second pick may follow the first pick in close succession, in which case the same disc continues its rotation, but on the other hand, the second pick may not be inserted until one or more picks have been inserted from any of the other three discs on the same side of the loom. In fact, a considerable number of picks from other discs 20 may separate first and second picks from one particular disc, and the length of weft 256 connecting the first pick to the trapper B may be subjected to tension as the first pick moves with the fabric towards the take-up roll. In order to avoid 25 straining or breakage of the weft during such interval, the trapper B in its position of rest has its grip relieved slightly by the low-lift cam 122 (see Figs. 12 and 14). The weft can thus pass slowly through the trapper until the disc again 30 comes into operation, when the trapper moves away from the cam 122 and again closes firmly on the weft.

When the disc is freed once more for the production of a loop to form the second pick, the trappers move counter-clockwise to bring the trapper A (still open) into engagement with the weft between the trapper B and the guide 251. The carrier pegs 133 pass between the trappers to engage this length of weft and draw the second loop 259 as shown in Fig. 43. No compensation in the loop length is necessary in this instance, the simple loop having to be merely of such length that together with the length 256 connected to the first pick, it forms a pick length.

The compensation effected in the drawing of the first pick is sufficient to enable the correct length of weft to be available in both first pick and second pick loops with the carrier pegs 133 releasing the loops at the same point in their travel. Thus, when the second loop is drawn to the full length, the pegs 133 are swung backwardly by the operation of the same teeth 236 as before; the trapper B releases the end of the loop 259 connected to the first pick 258, and the trapper A is closed to seize the end of the weft proceeding from the guide 251 and to sever the second loop from the supply. The notch 121 in the pad 102 of the trapper A ensures that the end of the loop 259 is not seized by the trapper.

The lead extension 124 on the head 106 of trapper B effects early release of the loop 259 to avoid straining the length 256 by reason of the movement of the trapper B. Closing of the trapper A (which has no extensions to its head 106) occurs slightly later so that cutting takes place while the pegs 133 are drawing the weft taut through the trapper, so giving clean cutting.

With the disc 30d, the loop limb connected to the non-cutting trapper B is presented to the shuttle on the first pick, and the trapper A is therefore timed for early release. Similarly, on the second pick, the trapper B has early release. There is thus no necessity for either lag or lead extensions on the trapper spindles, and the timing can be simply adjusted by regulating the pick loop 75

length of the cam run. The timing of the trappers on the reversing disc 30c is substantially similar to that of discs 30a, 30b.

The second loop 259 on release is presented to the dummy shuttle 257 and carried into the warps. This series of operations is shown in Fig. 44. The second half-revolution of the disc 30 comes to an end with the trappers A and B again in the positions shown in Fig. 37 so as to be in readiness for the formation of a loop for the first pick of a further connected pair of picks.

Fig. 14 shows clearly in the dotted positions of trappers A and B the small head 106 of the trapper A and the larger head of the trapper B, this latter including, in addition to the inward extension 123 for engagement with the cam 122, the lead and lag extensions 124, 1124. By the provision of the extensions 124, 1124, the timing of both opening and closing of the trappers A and B in the two half-revolutions of the disc 30 may 20 be caused to vary slightly for the purposes set out above, notwithstanding that both trappers are controlled by the same cam run 112, 113. Thus, while adjustments of the cams 112, 113, themselves affect both trappers equally, slight variations in timing can be effected by suitably dimensioning the extensions 124, 1124.

Since the rotation of the disc 30 is in such a direction that the trapping device B, which is holding the length 256 during the formation of a 30-second pick loop, is towards the fabric, the rotation of the disc does not put the length 256 under tension, release of the weft from the trapper B taking place as shown in Fig. 44 before the length 256 has been drawn taut. Apart, however, from this provision, it is necessary to arrange that the length 256 connecting a first pick inserted from any disc to the trapping device B of that disc must be arranged to lie out of the path of any of the carriers so that any disc can remain 40 idle after insertion of the first pick for any desired period of time.

Reference to the right-hand side of Fig. 1, which shows to a small scale the gear-box illustrated in the more detailed drawings, shows that 45 the lengths 256a, 256b and 256d from the upper disc 30a and the two lower discs 30b, 30d respectively at all times lie clear of the carriers. In the case, however, of the disc 30c, if the length 256c proceeded directly from that disc to the level of 50 the fabric, the length would lie across the path followed by the carriers and so would be broken. The hook mechanism shown in Figs. 23-28 is provided to enable the length 256c held by the disc 30c to be drawn into a position clear of the 55 carriers.

After the insertion of the first pick from the disc 30c the hook 191 controlled by the rotation of the disc itself advances until it engages the length 256c near the trapper B and then is withdrawn to pull the length into a loop consisting of the length 1257 lying below the level of the pegs 133 at the right-hand side of the chain (see Fig. 26), even when such pegs have been set to operate with the lower disc 30d. Between the hook and the trapper B the length 256c forms a short length 258 lying to one side of the pegs 133.

Since instead of the connecting length 256c proceeding direct to the edge 253 of the fabric from the trapper B, the weft proceeds in the length 258 in a direction away from the edge of the fabric, a counterclockwise motion of the disc 30c as in the case of the other discs 30a, 30b, 30d to commence the formation of a second 70 length 257 being 75

put under tension and possibly broken. It is for this purpose that the disc 30c is caused to rotate in a clockwise direction, i. e., in the opposite direction to discs 30a, 30b, and 30d.

the end of the shuttle and its point directed towards the middle of the shuttle. Pivotedly mounted at 273 on a bracket 274 carried by the lay 275 is a depresser lever 276 carrying at its forward end a plate 277 depending downwardly towards the channel 271 (see Figs. 3 and 29). A lever 278 connected to the lever 276 is connected by a link 279 towards the pivot shaft 280 of the lay swords 281. A bell-crank lever 282 operated by a cam 283 on the half-time shaft 284 is connected to the link 279 and enables the depresser lever 276 to be lowered sharply towards the shuttle. One depresser plate 277 is mounted above the path of the carrier pegs 133 on each side of each chain 5, the pair of depressers at each side of the loom being operated simultaneously by the common cam 283 to bring the limb of a weft loop drawn at either side of the chain towards the shuttle 257 as the shuttle is picked past the chain run.

15 It will be understood that at the left-hand side of the loom similar provision has to be made to withdraw one of the lengths 256 out of the paths of the carrier. In this case, however, it is the length 256a proceeding from the upper left-hand disc which has to be withdrawn instead of the one from the upper right-hand disc as in the case of the right-hand gear-box. Such a length 256a is shown drawn aside in Fig. 1. Apart from the left-hand disc 30a being the one with a reverse rotation, as previously described, other modifications are provided between right- and left-hand gear-boxes for this and other functions of the boxes, as will be described in detail hereafter.

The levers 276 are so positioned that the plates 277 engage the loops 254, 259 by the limbs remote from the chains 5, but do not touch the nearer limbs. The plate 277 on the end of the lever 276 may have a recess 285 (see Fig. 2) to form a bridge wide enough to ensure that it engages the limb of the weft loop correctly to carry it into the channel 271 on the shuttle and so under the prong 272 for insertion into the warps.

As is clear from Figs. 37-45, the guide 251 is placed so as to lead the weft 250 to the disc just to one side of the trapping device which for the time being is free from the weft. Guides 251a, 251b of the discs 30a, 30b are carried by the cross-bars of the forks carrying the teeth 145b, 145a from the levers 146, 147, thus leading weft threads to the discs somewhat to the right of the nearer trapping devices, (B in Fig. 37; A in Fig. 42. The disc 30c having the reverse rotation has its guide 251c also carried by the cross-bar carrying the guide 251a, so as to lead the weft somewhat to the left of the nearer trapping device (A in Fig. 45).

Fig. 29 shows the depresser mechanism in greater detail, and also a modified form of depresser plate which is bifurcated at its lower end to carry the weft below the level of the prong 272 at both sides of the channel 271. The depresser carries the weft between the gap 286 between the front edge of the bracket 274 and the top edge of an angle-iron 287 lying below the chain 5 and, by forming a continuation of the front wall of the shuttle box 288, constituting a guide for the shuttle as it passes into the warps. The weft is therefore placed with certainty below the prong 272 and is also kept out of contact with the shuttle body so that there is no danger of the shuttle dragging the weft from under the depresser 271.

Though the cross-bars are movable with the levers 146, 147, they remain stationary during loop drawing, and, when stationary, the guides 45 251a, 251b, 251c are at the correct level to deliver the weft directly into the open trapping devices.

The guide 251d serving the disc 30d which rotates in the same direction as the discs 30a, 30b is carried by the bracket 1251 so as to lead its weft also to the right of the nearer trapper.

As the shuttle travels through the warps, the weft slips round the base of the prong 272 to the side of the rear end of the shuttle into the warps, without danger of being trapped against the reed. The end of the weft falls cleanly away from the shuttle as the other side of the fabric is reached. 50

Controlling mechanism

The shaft 78 by which the slide 81 is operated to determine whether a left-hand or a right-hand disc is to rotate passes rearwardly from the gear box to the plate 11 above the radius rods 10, being freely mounted in the plate 11 and itself forming a bearing for the sleeve 77 by which it is surrounded. The sleeve 77 terminates at a suitable point along the shaft 78 for the levers 90, 91 C to be connected by the cords 92 to a convenient controlling mechanism on the loom, e. g. a dobby or jacquard mechanism.

Since the sleeve 77 controlling the slide 69 makes a selection between upper and lower pairs of discs and the shaft 18 controlling the slide 81 makes a selection between left- and right-hand pairs of discs, all possible combinations of the positions of the shaft and the sleeve to select any one of the discs 30a, 30b, 30c, 30d for rotation are achieved solely by the two cords 92, so that two pin positions in a dobby chain or the allocation of two hole positions in each card of a jacquard is all that is required to make the necessary weft selection at one side of the loom. 75

Presentation of loops to shuttle

The dummy shuttle 251 shown in Fig. 34 has a channel 271 on its upper surface, and lying within each end of the channel is a prong 272 extending longitudinally of the shuttle, with its base near

Similar pairs of cords are arranged at the two sides of the loom, one pair controlling each gear box 1. It will be understood that instead of dobby or jacquard control, any other of the well-known expedients used on looms, e. g. tappets, may be employed for weft selection.

Differences between right- and left-hand gear boxes

- 10 The gear-box described in Figs. 4-28 and 31 and 32 is the one intended for the right-hand side of the loom as is evident from the disposition of the disc 30c necessitating the provision of the weft hook 191. The gear-box at the left-hand side of the loom is of identical construction, provision, however, being made in the design of the gear-box to provide for left-hand working. In the first place, instead of the bottom disc 30b, 30d rotating in the same direction as the disc 30a, they have to rotate similarly to disc 30c. As previously explained, this reverse rotation is effected by inversion of the gears 32b, 32d and the transfer of the pinions 181, 182 to connect gears 32b and 31b indirectly, leaving gears 32c and 31c directly connected.
- 20 The cam plate 204 for the weft-hook is reversed and transferred from the wall of the shaft 24 to the wall of the shaft housing 23, alternative fixing holes 204x, 204y (Fig. 4) being provided for the purpose. The weft hook lever 199 is removed from the right-hand pivot 198x to the left-hand pivot 198y and the rimmed member 56a is provided with the bridge 192 instead of the rimmed member 56c, the lever 194 engaged by the rollers 193 on the bridge 192 being transferred from the pivot 195x to the pivot 195y (Fig. 5). Similarly, the return spring 202 connected to the upper end of the lever 199 is transferred to an appropriate position.
- 30 In like manner the compensator link 210 is transferred from the hole 210x to the hole 210y on the left-hand side of the gear-box, and the levers 214, 216 engaged by the cams 219a, 219b, 219c, 219d are transferred from the pivots 215x, 215y, 217x to the pivots 215y, 217y (see Fig. 31). The left-hand lever 216 is now provided with a head 213 to engage the link 210. It is also necessary to rotate the shafts 33, 34 and the gears 32a, 32b somewhat to bring the cams 219 to a position which is a mirror image of that shown in Fig. 31. The link 210 thus lies to the left-hand side of the left-hand chain run, the spindle 230 forming the pivot for the lever 229 being extended through the bracket 221 to the left of the chain run to receive the lever 228 to which the link 210 is connected. This "handing" of the link 210 is not absolutely necessary, but it is convenient to remove the link from the side of the unit nearest the warps, since this space is frequently required for selvedging harness. The guide 251d is transferred to the dotted position shown in Fig. 20 and the guide 251b is mounted on the wall of the housing 23 by a plate similar to the plate 1251 so as to direct the threads correctly to the reversed discs 30d, 30b.

Adjustment for width of fabric

- As shown in Figs. 1 and 2 the weft measuring devices at two sides of the loom are adjusted for the weaving of relatively narrow fabric, the chain runs being brought as near as practical to the edges 253 of the fabric so as to keep to a minimum the weft lengths 256 extending between the inserted first picks and the trapping devices.
- 75 In order to enable the measuring apparatus to

be adjusted for different widths of fabric, the gear boxes can be slid along the front rail 8 of the loom to any desired position, bolts 300 being provided to hold them firmly in position. The rear chain sprockets 1 can similarly be slid along the driving shaft 2, each sprocket being held in any required position by means of a set screw 301. The plate 11 slides with the gear 1, and since the plate 11 is connected to the gear box by the radius rods 10, the whole measuring apparatus 10 can be moved bodily, and since the drive of the measuring apparatus is always maintained through the shaft 2, weft loop formation can be made at any position in the measuring apparatus with very few adjustments other than those mentioned.

It is, however, necessary to change the length to which the weft loops are drawn in accordance with the width of the fabric. This is primarily effected by adjusting the position of the members 235 carrying the teeth 236a, 236b, 236c, 236d so as to cause the carrier pegs 133 to be thrown back after the necessary length of run from the discs 30a, 30b, 30c, 30d. With adjustment of the positions of the members 235 on the levers 146, 147 the pivots 148 of the levers may be adjusted along the guides 140, 141 so as to limit the extent of movement of the teeth 236a, 236b, 236c, 236d, upwards or downwards with respect to the chain run.

Compensation of the length of the first pick loops can be adjusted by altering the effective length of the rods 233a, 233b, 233c, 233d from their spindles 229, 230, the rods being in position by set screws 302. These set screws also enable the compensation for any particular disc to be adjusted with respect to the others. In particular, with the carriers for inside and outside discs being arranged to draw off their loops after the same length of chain run, greater compensation must be provided for the first picks drawn from outside discs because of the greater length 256 to be provided between these discs and the edge of the fabric, as well as in the case of the disc having the reverse rotation for the length of weft 45 required in the loop must provide the lengths 1257, 258.

Thus, as far as loop drawing is concerned, mere bodily adjustment of the weft measuring apparatus, coupled with adjustment of the carrier release positions and the amount of compensation, is all that is necessary. Minor adjustment of trapper timing is effected by means of the worms 115, these being readily accessible for use with a turn-screw.

Since the weft measuring apparatus lies close to the end of the reed 303, reeds appropriate to the width of the fabric must be employed. Instead, therefore, of the reed 303 being secured to the lay swords 281, dummy lay swords 304 secured to the lay 275 are provided, these being made of angle-iron forming brackets to which the reed is secured by bolts 305. The angle-irons extend downwardly to the shaft 280 carrying the normal lay swords 281, this construction holding the reed 303 rigid on the lay 275.

Whatever the width of the fabric, the dummy shuttle 251 is picked across the whole width of the loom between the shuttle boxes 288, the depressers 271 which, of course, are movable with the weft measuring apparatus, serving to bring the weft loops downwardly for engagement by one or other of the prongs 272 on the shuttle as the shuttle passes between the shuttle box 288 and the edge 253 of the fabric. In order to pro-

vide for accurate guiding of the shuttle 257 when the weft measuring apparatus is not in its widest position, a piece 307 of appropriate length is secured to the lay to form an extension of the back 308 of the shuttle box 288. The angle iron 287 is secured to the lay opposite the extension 307 to guide the front edge of the shuttle 254. The guide 287 extends under the chain run and terminates relatively closely to the edge 253 of the fabric.

The adjusting means thus enable the weft measuring apparatus to be moved to the full width of the loom, the gear box in the widest adjusted position lying partly above the side frames 309, and the compensator links 210 lying just inside the bull-horns 310 by which the dobby or jacquard mechanism is carried.

The dummy lay-swords 281 are movable along the shaft 280 in accordance with the fabric width, 20 and the depresser levers 278 and their operating cams 283, together with the connecting levers and links, are similarly adjustable in position.

When the pick ends are released as the shuttle passes out of the warps they may be seized by the suction-trapping arrangement described in U. S. application S. No. 526,317 filed March 30th, 1931, the suction openings 410 in the shuttle-race being suitably positioned in accordance with the width of the fabric in the manner described in that specification. Operation of the trapping mechanism is effected through links 311 and levers 312 from cams 313 on the shaft 284. The levers 312 are slidably mounted on a rod 314 and are connected by a cable 315 to the starting-handle 316 of the loom. When the loom is stopped, the cable 315 pulls the levers 312 to the right along the rod 314 so that the levers cannot remain lifted by the cams 313. Consequently, the levers are in inoperative position and suction power is not wasted while the loom is idle. As soon as the loom is re-started, the cable 315 is slackened and a spring 317 returns the levers 312 to operative position on the cams 313. Each of the levers 312 is extended forward beyond its connection with its link 311 to terminate in a pedal 318 at the front of the loom. These pedals enable the suction openings 410 to be freed for tensioning and securing weft-ends during starting up when the loom is stopped.

Minor features of construction

Most of the moving parts of the weft measuring apparatus are either enclosed in the gear-box or guarded by the gear-box and the weft packages 260 above the box. Below each chain run is a guard 319, e. g. of tin-plate, extending forwardly towards the bracket 274 (Fig. 29) to support the weft-loops when they are released from the carrier pegs 133 to be carried into the warps by the shuttle 257.

A chain guard 320 (Fig. 3) is provided round the front sprocket 6 and a further guard 321 round each rear sprocket 1. The rear sprocket of the gear 3 connecting the shaft 2 with the crank 65 shaft 4 is also protected by means of a guard 322 (see Fig. 2). The shaft 2 is protected between the bearings 12 secured to the side frames 309 and the guards 321 by stationary sleeves 324 of appropriate length. Between the guards 321, telescoping sleeves 325, 326 are provided which can be extended and contracted in accordance with the position to which the measuring apparatus is brought. The operative in attending to broken warps etc. can thus lean over the shaft 2 without 70 being endangered by its rotation.

It may be advisable in fitting the attachment to different types of loom to employ different distances between the chain wheels 1 and 6 and then to adjust the chain speed to bring the carrier pegs 133 past the gear-box 7 at every other pick. Since, however, the gear-box is driven by the chain 5, suitable adjustment of the chain-wheel 6 is necessary in order to cause any one disc to make one half-revolution during the time occupied by two picks.

Differently sized chain-wheels can be secured to the differential housing 52, but the height of the spindles 48, 49 of the differential must be adjusted to bring the lower run of the chain 5 as it leaves the lower side of the chain-wheel 6 into line with the guides 140, 141. For this purpose the spindles 48, 49 are carried in housings 330, 331 pivoted on the spindles 44, 45 and adapted to be secured over a limited range of angular positions by means of bolts 332. Since the pairs of gears 46, 47 are centered on the spindles 44, 48 and 45, 49 respectively, such adjustment of the housings 330, 331, and with them the differential housing 52 and chain-wheel 6, can be readily effected without bringing any gears out of mesh. The bolts 332 engage slots 333 on the extensions of the gear-box housing the helical gears 42, 43 and hold the housings 330, 331 firmly in any adjusted position. Fig. 33 shows in chain lines how two differently sized wheels 6 can be accommodated and the necessary adjustment of the height of these wheels.

General operation

With four weft packages 260 provided on each side of the loom, as many as eight different wefts may be inserted into the warps, a pick from one side of the loom being followed by a pick from any of the packages at the other side of the loom, in a sequence determined by the dobby, jacquard, or other mechanism controlling the cords 92. A change in weft at any gear-box 7 may take place at every other pick or two or more picks of the same weft may follow each other from that box. If there are packages of the same weft at both boxes, any desired number of consecutive picks may consist of such same weft.

Therefore, between the possibilities of having a weft change at every pick and having any desired length of fabric woven with no weft-change, the weft-selecting mechanism offers enormous scope in the weaving of patterned fabrics. The differences in the wefts may be, e. g. differences of colour, lustre, denier or count, extent and/or direction of twist, and material, or combinations of any of these. Used, moreover, in conjunction with dobby or jacquard mechanisms, the invention increases enormously the range of effects obtainable by rendering available a large variety of wefts without necessitating stoppage of the loom until the supply is exhausted. Since all the packages can be of very large size, weft-replenishment need only take place at very long intervals, especially if consumption from each of the supply packages is at substantially the same rate.

As previously stated, the suction-trapping arrangement described in U. S. Pat. No. 1,921,396 enables the free ends of the picks to be seized as they are released from the shuttle. This enables the picks to be correctly tensioned and beaten up straight. After beat-up the projecting ends are severed and the short portions sucked away as described in U. S. Patents Nos. 1,921,396 and 1,963,098. To sever the ends, a

trimmer of the type described in U. S. Patent No. 1,966,935 may be used, and, if desired, the finished fabric may be cropped to bring the projecting ends quite close to the selvedge. In order to stop the loom on failure to lay weft correctly, a weft-stop mechanism operating on the trapped projecting ends may be used, as is described in U. S. application S. No. 628,983 filed August 16th, 1932. This mechanism engages the end of a pick between the edge of the warps and the suction-opening 410 by which it is held so that absence or incorrect tensioning of every pick is detected, the other end (in the case of the first of a pair of connected picks) being connected to the supply 260, or (in the case of a second pick) to the already laid first pick. Breakage or exhaustion of weft thus results in a stoppage of the loom and incorrect patterning is avoided.

What I claim and desire to secure by Letters Patent is:—

1. Weft-measuring apparatus for shuttleless looms in which weft is drawn in loop lengths prior to insertion into the warps, said apparatus comprising a plurality of movable trapping means, drawing means movable with respect to the said trapping means, means to move each of the trapping means separately to enable each such means to draw a length of weft trapped therein from a supply, and selector means adapted to bring about engagement between the trapping means and the supply of the drawing means with the length of any particular weft drawn from its supply by one of the trapping means.

2. Weft-measuring apparatus for shuttleless looms in which weft is drawn in loop lengths prior to insertion into the warps, said apparatus comprising a plurality of movable trapping means, drawing means adapted to engage weft held at any one of said trapping means, means to hold the trapping means in a position where the weft will not be engaged by the drawing means, selector means adapted to free any one of said trapping means, and means to move said selected trapping means to bring weft held by the trapping means into position to be engaged by the drawing means.

3. Weft-measuring apparatus for shuttleless looms in which weft is drawn in loop lengths prior to insertion into the warps, said apparatus comprising a plurality of movable trapping means, drawing means adapted to engage weft held at any one of said trapping means, means adapted to move any trapping means so as to bring weft held thereby into position to be engaged by the drawing means, selector means adapted to permit movement of any desired trapping means, and locking means controlled by the movement of the selected trapping means to prevent movement of other trapping means.

4. Weft-measuring apparatus for shuttleless looms in which weft is drawn in loop lengths prior to insertion into the warps, said apparatus comprising a plurality of movable trapping means, a plurality of drawing means adapted to engage weft held at said trapping means, and selector means adapted to bring one of said drawing means into position to engage weft at any desired trapping means.

5. Weft-measuring apparatus for shuttleless looms in which weft is drawn in loop lengths prior to insertion into the warps, said apparatus comprising a plurality of movable trapping means, a drawing member movable past said trapping means, a carrier movably mounted on said member, and selector means adapted to

move the carrier on said member so that it is brought by the movement of the member into engagement with weft held at one of the trapping means.

6. Weft-measuring apparatus for shuttleless looms in which weft is drawn in loop lengths prior to insertion into the warps, said apparatus comprising a plurality of movable trapping means, a drawing member movable past said trapping means, a plurality of carriers movably mounted on said member, and selector means adapted to move one of said carriers on said member so that it is brought by the movement of the member into engagement with weft held at one of the trapping means. 5

7. Weft-measuring apparatus for shuttleless looms in which weft is drawn in loop lengths prior to insertion into the warps, said apparatus comprising a plurality of movable trapping means, a drawing member movable past said trapping means, a plurality of carriers movably mounted at spaced intervals on said member, and selector means adapted to move the carriers on the member so that each in turn engages weft held at one of the trapping means. 10

8. Weft-measuring apparatus for shuttleless looms in which weft is drawn in loop lengths prior to insertion into the warps, said apparatus comprising loop drawing means, a differential driving mechanism, movable trapping means in driving connection with each side of the differential mechanism respectively, said trapping means being adapted to present weft held thereby to the drawing means, and selector means adapted to lock against movement the trapping means driven from one side of the differential mechanism so that the drive of the differential mechanism is transmitted to the trapping means connected to the other side and weft is thereby presented for loop drawing by the trapping means at such other 20 side. 25

9. Weft-measuring apparatus according to claim 8 comprising further differential driving mechanism at at least one side of the said differential mechanism, a pair of movable trapping means in driving connection respectively with the two sides of the further differential mechanism, the selector means being adapted to lock one or both of the trapping means of the further differential mechanism against movement. 40 50

10. Weft-measuring apparatus for shuttleless looms in which weft is drawn in loop lengths prior to insertion into the warps, said apparatus comprising a plurality of movable trapping means, a drawing member movable past said trapping means, means adapted to move the trapping means so as to bring weft held thereby across the path of said drawing member, selector means adapted to bring about such movement of any particular trapping means, at least one carrier movably mounted on the drawing member, means adapted to hold said carrier in a position on the drawing member where it would not engage weft presented by the trapping means, and means disposed on the path of the drawing member in advance of the trapping means to move the carrier into position to engage the weft presented by the selected trapping means. 60 65

11. Weft-measuring apparatus for shuttleless looms in which weft is drawn in loop lengths prior to insertion into the warps, said apparatus comprising four trapping means arranged in two opposed pairs, a loop drawing member disposed for movement between said pairs, a pair of carriers movably mounted on said member and lying 70 75

on opposite sides thereof, means to move said member so as to draw the carriers past the trapping means, means to move the trapping means so as to bring weft held thereby across the paths 5 of the carriers, selector means adapted to move both carriers towards one of each pair of trapping means respectively, and further selector means adapted to move one of said carriers away from one trapping means, so leaving only the 10 other carrier in a position to engage the weft presented by the other trapping means.

12. Weft-measuring apparatus for shuttleless looms in which weft is drawn in loop lengths prior to insertion into the warps, said apparatus 15 comprising a plurality of movable trapping means, drawing means, means to move the drawing means past said trapping means, means to move the trapping means so as to present weft held thereby to the drawing means, carrier means 20 movably mounted on the drawing means in normally inoperative position, selector means adapted to bring about movement of one trapping means into weft-presenting position, means to move said carrier means into position to engage the 25 presented weft so as to draw it into a loop, means to move the carrier means so as to free the loop therefrom and to return the carrier means to inoperative position.

13. Weft-measuring apparatus for shuttleless 30 looms in which weft is drawn in loop lengths prior to insertion into the warps, said apparatus comprising a plurality of movable trapping means each comprising two trapping devices, a loop drawing member, means to move the loop drawing member past the trapping means, means to move each trapping means so that weft held in one trapping device thereof is presented to the drawing member and engaged by the other trapping device, selector means adapted to free one of 35 the trapping means for weft presentation, means to free the length of weft drawn by the drawing member from the one trapping device of the freed trapping means, and means to trap the weft in the other trapping device in readiness for a further weft-presenting movement of that trapping means.

14. Weft-measuring apparatus for shuttleless 40 looms in which weft is drawn in loop lengths prior to insertion into the warps, said apparatus comprising a plurality of movable trapping means, drawing means adapted to engage weft held at any one of said trapping means, selector means adapted to bring about engagement between the drawing means and any particular 45 weft held by the trapping means, and cutting means controlled by the movement of the trapping means to cut a weft thread after every other weft-presenting movement of the trapping means for that thread.

15. Weft-measuring apparatus for shuttleless 50 looms in which weft is drawn in loop lengths prior to insertion into the warps, said apparatus comprising a plurality of rotatable members, a pair of diametrically opposed trapping devices 55 mounted on each of said members, means adapted to rotate said members, locking means adapted to prevent rotation of the members, selector means adapted to free one of the members for rotation, a loop drawing member movable past the rotatable members, weft held in one of a pair of trapping devices being brought by one 60 half-revolution of the member carrying the devices into position to be engaged by the loop drawing member and also by the other trapping device in readiness for further loop drawing in

the next half-revolution of the member, and cutting means operable in conjunction with one of each pair of trapping devices to sever the weft after any one rotatable member under the control of the selector means has made two half-revolutions to allow the drawing means to form two loops in any one weft. 5

16. Weft-measuring apparatus for shuttleless 10 looms in which weft is drawn in loop lengths prior to insertion into the warps, said apparatus comprising four rotatable members, a pair of trapping devices carried by each member, cutting means in association with one of each pair of trapping devices, two differential mechanisms, the two sides of each mechanism being in driving connection with two of the rotatable members, a further differential mechanism in driving connection on its two sides with the two first-named differential mechanisms respectively, means adapted to free one and lock the other of 15 the two differential mechanisms, means adapted to lock and to free two rotatable members driven by different differential mechanisms and lock the other two rotatable members, the two sets of means thus operating to free one only of the 20 rotatable members for rotation, selector means controlling the said freeing and locking means, and a loop drawing member movable past the rotatable members and adapted to engage weft held in one of the trapping members on the freed 25 rotatable member and draw it into a loop.

17. Weft-measuring apparatus according to 30 claim 16 wherein the means for freeing the rotatable members co-operate with means rotatable with the members to permit a half-revolution of 35 a freed rotatable member, and, during such half-revolution, to prevent freeing of the other rotatable members.

18. Weft-measuring apparatus according to 35 claim 16 wherein the means for freeing the rotatable members cooperate with means rotatable with the members to permit a half-revolution of 40 a freed rotatable member, and, during such half-revolution, to prevent freeing of the other rotatable members, and wherein the selector means 45 include spring means permitting selection to be made during the rotation of one rotatable member, such selection being only effective after completion of a half-revolution by that member.

19. Weft-measuring apparatus according to 50 claim 16 comprising compensating means disposed along the path of the loop drawing member to engage weft loops drawn thereby and draw an additional length of weft in any loop, cam means 55 rotatable with each rotatable member, and means connecting said cam and compensating means, the cam means only making contact with said connecting means during every other half-revolution of any of the rotatable members to draw additional weft into the loops formed only during 60 such half-revolutions.

20. Weft-measuring apparatus according to 65 claim 16 comprising a pair of carriers movably mounted on the drawing member, selector means controlled by the rotation of two of the rotatable members driven by different differential mechanisms to effect a movement of both carriers towards or away from said two rotatable members or the two remaining members respectively, further selector means controlled in accordance 70 with the freeing and locking of the member-driving differential mechanism to effect a movement of one of the carriers away from one of the rotatable members towards which it has been brought by the first-named selector means, the 75

two sets of selector means thus operating to leave one carrier in weft-engaging position with respect to the one member freed for rotation.

21. Shuttleless loom in which weft is drawn in 5 loop lengths prior to insertion into the warps, said loom comprising at least one side of the warps weft-measuring apparatus including a plurality of movable trapping means, drawing means adapted to engage weft held in any one of said 10 trapping means, selector means adapted to bring about engagement between the drawing means and any particular weft held by the trapping means so as to draw a loop therein, weft inserting means adapted to carry into the warps pick 15 lengths of weft from loops of any thread, and means to sever each weft from its supply package only after the drawing of two pick lengths of that weft, so that each weft is inserted in the form of pairs of connected picks.

22. Shuttleless loom in which weft is drawn in 20 loop lengths prior to insertion into the warps, said loom comprising at least one side of the warps weft-measuring and presenting apparatus including a plurality of movable trapping means, 25 drawing means adapted to engage weft held in any one of said trapping means, selector means adapted to bring about engagement between the drawing means and any particular weft held by the trapping means so as to draw a loop therein, 30 and weft inserting means adapted to carry into the warps pick lengths of weft from loops of any thread, said weft-measuring and presenting apparatus being adjustably positioned with respect to the side of the loom in accordance with the 35 width of the fabric being woven.

23. Shuttleless loom according to claim 22 comprising a shuttle race adapted to carry a dummy shuttle, picking boxes at the ends of said race, a reed on said race, weft-measuring apparatus mounted in a position lengthwise of the loom between a picking box and an end of the reed, and guide members for the dummy shuttle mounted on the shuttle race between the picking box and the end of the reed. 5

24. Shuttleless loom according to claim 22 comprising a driven shaft extending lengthwise of the loom, a chain sprocket on said shaft, and a chain driven by said shaft, the adjustably positioned weft-measuring and weft-presenting apparatus being driven by said chain and said chain 15 sprocket being adjustably mounted on the shaft in a position corresponding to the position of the weft-measuring and weft-presenting apparatus.

25. Shuttleless loom according to claim 22 comprising a driven shaft extending lengthwise of the loom, a chain sprocket on said shaft, a chain driven by said shaft, said chain driving the adjustably positioned weft-measuring and weft-presenting apparatus and said chain sprocket being adjustably mounted on the shaft in a position 20 corresponding to the position of the weft-measuring and weft-presenting apparatus, a bracket mounted on the driven shaft and surrounding the chain sprocket, and means connecting the bracket and the weft-measuring and weft-presenting apparatus to enable the chain sprocket to be moved 25 as a unit lengthwise of the loom. 30
